UNITED STATES PATENT OFFICE.

WILLIAM R. LANDY, OF MINNEAPOLIS, MINNESOTA.

SHOE-BUFFER.

1,115,468.

Specification of Letters Patent. Patented Oct. 27, 1914.

Application filed May 31, 1913. Serial No. 770,904.

To all whom it may concern:

Be it known that I, WILLIAM R. LANDY, a citizen of the United States, residing at Minneapolis, in the county of Hennepin and State of Minnesota, have invented a new and useful Improvement in Shoe-Buffers, of which the following is a specification.

This invention has for its object the production of a simple and inexpensive shoe buffer which is adapted to be effective in operation and upon which the polishing material is flexibly supported and any slack may be taken up from time to time and also the provision of a handle on the buffer in which the polishing material and brushes may be kept when not in use.

Further objects and improved details of construction will be apparent from the following description and the particular novelty of the invention will be pointed out in the claims.

In the drawing, Figure 1 is a perspective of the invention the cover on the handle being illustrated in partly open position; Fig. 2 is a plan of the invention; Fig. 3 is a cross section through the median portion of the device and Fig. 4 is a section of a detail.

In the drawing A indicates a handle and B a removable cover, said parts coöperating together to form an oblong receptacle. The body of the handle is mounted upon a quadrilateral frame 2 made of metal wire or other suitable material to which the side edges 3 and 4 of a thin transversely disposed metal plate are secured by bending over the wire. This plate is formed into two opposite sides 5 and 6 and a floor 7 of said receptacle. To the end portions of the frame 2 two opposite ends 8 and 9 of a longitudinally disposed resilient plate 11 of metal or other suitable material are secured by turning the metal over said wire, said longitudinal plate being formed with substantially vertical ends forming walls 10 which serve to close the ends of said receptacle.

The median portion 11 of the longitudinal plate is integral with the end walls 10 and curves downwardly like a bow below the floor of the handle and forms a resilient supporting surface for the polishing material C. The plate 11 corresponds substantially with the width of the handle and near the upper portion of each of its end walls 10 a pair of side flanges 12 are struck out and away from the body of the handle

and form pivot supports in which clasps 13 are journaled.

Each clasp has a handle portion 14 and a short jaw 15 set at an angle to said handle portion and having a serrated lower edge. These members are supported axially by end pivots 16 which project freely through the flanges 12 allowing the clasp to be turned down into the position illustrated in Fig. 4 to engage and hold in adjusted position the opposite ends of a strip of cloth 17 or other suitable material upon the outer surface of which the strip of buffing material 18 is secured. The teeth of the jaw 15 engage the strip 17 and hold it tightly impinged against the outer surface of the end wall of the handle. The strip of cloth 17 extends longitudinally over the lower surface of the resilient supporting plate 11 and has its side edges turned in at 19 to engage and hold said strip upon said resilient support.

The buffing material 18 is made out of a strip of sheep's skin with the wool on, or other suitable material, of substantially the same width as the resilient support 11 and is secured to the outer surface of the strip 17 by its ends being stitched at 20 or otherwise fastened thereto. In use any slack which from time to time may occur in the polishing material and its supporting strip 17 may be taken up by adjusting the strip below the clasps on the opposite ends of the handle. The body of the handle has its cover secured thereto by inturned side flanges 21 which project downwardly over the side portions 3 and 4 of the frame 2. The frame 2, cover B, resilient supporting plate 11, and strips 17 and 18 converge longitudinally in the same direction, whereby the cover may be placed over the top of the handle in the position illustrated in Fig. 1 and then slid forward until its inturned edges 21 engage the frame 2 when the cover is fully closed. The tapering of the frame 2 and cover as specified enables the cover to be adjusted to or removed from the handle without having to slide the cover the full length of the handle which is an advantage.

In use the buffer is reciprocated by hand in the usual manner to polish a shoe and should the polishing material become slack through use it may be adjusted by means of the clasps to take up any slack. The in-turned side edges 19 of the cloth strip also serve to limit side movement of the buffer

supporting strip 17 on the flexible metal buffer supporting plate 11 and said flexible plate 11 serves to produce a resilient support for the buffer, the resiliency being increased by the outward spreading movement of plate 11 which occurs at the ends of the handle through the construction employed. This metal flexible plate 11 also performs the function of closing the ends 10 of the handle which saves material in constructing the handle.

The construction of my invention is light and durable as well as cleanly in use and is particularly effective on account of the resiliency support which is provided and the adjustability of the buffer longitudinally for the purpose of taking up slack.

In accordance with the patent statutes I have described the principles of operation 20 of my invention together with the apparatus which I now consider to represent the best embodiment thereof but I desire to have it understood that the construction shown is only illustrative and that the invention 25 can be carried out by other means and applied to uses other than those above set forth within the scope of the following claims.

Having described my invention, what I 30 claim as new and desire to protect by Letters Patent is:—

1. A shoe buffer, comprising in combination, a handle having a quadrilateral frame, a transverse plate having ends secured to the sides of said frame and forming side 35 walls and a floor of a receptacle, a longitudinal plate secured by its ends to the ends of said frame and having end portions forming end walls of said receptacle and a body portion bowed down below said floor from said end walls and forming a resilient 40 support, buckles mounted upon said end walls, a flexible strip stretched over the outer surface of said longitudinal plate and secured in adjusted position by said 45 buckles, and a strip of polishing material

secured over the surface of said flexible strip.

2. A shoe buffer, comprising in combination, a handle having a quadrilateral frame, a transverse plate having ends secured to the sides of said frame and forming side walls and a floor of a receptacle, a longitudinal plate secured by its ends to the ends of said frame and having end portions forming end walls of said receptacle and a body portion bowed down below said floor from said end walls and forming a resilient support, a flexible strip stretched over the outer surface of said longitudinal plate and having side edges projecting up and inwardly over the side edges of said plate, means for securing the ends of said strip to the end walls of said receptacle and a strip of polishing material mounted upon the outer surface of said flexible strip. 65

3. A shoe buffer, comprising in combination, a handle having a quadrilateral frame, a transverse plate having its ends secured to the sides of said frame and forming the sides and floor of a receptacle, a longitudinal plate secured by its ends to the ends of said frame and having end portions forming end walls of said receptacle and a body portion bowed down from said end walls below said floor and forming a resilient support, a flexible strip stretched over the outer surface of said longitudinal plate and resiliently supported thereby, means for securing the ends of said strip to the end walls of said receptacle and a strip 70 of polishing material secured over the outer surface of said flexible strip. 75

In testimony whereof, I have signed my name to this specification, in the presence of two subscribing witnesses.

WILLIAM R. LANDY.
